UNITED STATES PATENT OFFICE.

WILLIAM S. WESTON, OF CHICAGO, ILLINOIS.

ANTICREEPER FOR RAILWAY-RAILS.

1,120,258.

Specification of Letters Patent.

Patented Dec. 8, 1914.

Application filed February 13, 1914. Serial No. 818,463.

To all whom it may concern:

Be it known that I, WILLIAM S. WESTON, a citizen of the United States, residing in the city of Chicago, county of Cook, and 5 State of Illinois, have invented certain new and useful Improvements in Anticreepers for Railway-Rails, of which the following is a full, clear, and exact description.

My invention relates to anti-creepers for 10 railway rails which have a friction grip on the base of the rail and a pendent lug bearing against the tie, and more particularly to that class of anti-creepers which are made of resilient material on a form somewhat 15 smaller than the base of the rail onto which they are to be sprung by force in the process of installation.

The objects of my invention are, first, an anti-creepers of simple form that can be 20 made in a forging or bending machine in one piece without waste of material; second, an anti-creepers of the class described that can be applied to the rail base easily by hand with the aid of the ordinary hand or 25 spike hammer without the need of a special wrench or tool; and third, an anti-creepers with a moderate amount of adjustment in its installation, making it possible to select from a small number of standard sizes an 30 anti-creepers which will fit the base of any railway rail. The novel construction whereby I attain these objects, and other novel features of improvement, are hereinafter described and clearly illustrated in the accompanying 35 drawings which form a part of this specification, and are particularly pointed out in the claims.

In the drawings, Figure 1 is a side elevation of a railway rail showing an anti-creepers in operative position with a depending end portion abutting against a tie or other substructure. Fig. 2 is an end elevation of a rail with the anti-creepers in operative position. Fig. 3 is a plan view of 45 Fig. 1. Figs. 4 and 5 are end views of a rail showing the anti-creepers in consecutive stages in the process of its installation on the rail. Fig. 6 is another plan view showing the anti-creepers in conjunction 50 with an auxiliary clip, and Fig. 7 is a cross section on the line 7—7 of Fig. 6.

The same numerals refer to the same or similar parts in the several views.

My invention consists in an anti-creepers 55 made from a piece of steel rod, preferably round, cut without waste and forged or bent

into such shape that its component parts, as seen in a downward or plan view, will be disposed, relative to each other and to the rail, substantially in accordance to the following description: The rod is bent into a V at an angle something less than 90 degrees, with the legs offset so that when one leg is passed diagonally under the base of the rail, the other leg will extend lengthwise of the rail and above the upper face of the base flange. The central portion of this longitudinally disposed leg is bent inward toward the rail so as to overlap the flange, while its free end is bent downward 65 in a vertical direction passing the edge of the flange and forming the tie abutting portion of the anti-creepers. The free end of the diagonal leg of the V passed under the rail is bent upward past the edge of the 70 base flange on that side forming a short hook approximately at right angles to the leg but slightly inclined over the edge of the base flange toward the opposite leg.

Referring to Figs. 1, 2 and 3 of the 80 drawings, and retaining the nomenclature describing the anti-creepers as of V form, 1 is the leg diagonally or angularly disposed beneath the rail base, 2 is the longitudinally disposed leg with its central portion 3 bent 85 inward over the base flange and its free end 4 bent downward. The portion 5 is the offsetting connection between the legs at the apex of the V and 6 is the upturned hook in the free end of the diagonal leg. 90 The part 5 at the apex of the V and the downwardly bent or pendent part 4 furnish two points of contact, 7 and 8 respectively, between the anti-creepers and the edge of one base flange, determining 95 the exact position of the longitudinally disposed leg, while the upwardly bent hook 6 at the end of the diagonal leg furnishes a single point of contact 9 on the edge of the opposite base flange. These three points 100 of contact constitute three seats of effective bearing between the anti-creepers and the rail, and are described at greater length later on.

The anti-creepers is manufactured with 105 the angle of the V less than is required by the base of the rail on which it is to be used, that is, the perpendicular distance from the single point of contact on one side to a line through the two points of contact on the other side is less than the width of the base. This contracted construction is 110

illustrated in Fig. 3 by a dotted outline 6^a of the upturned hook 6, the ultimate location of the hook when in correct position on the rail being shown in heavy full lines. 5 The construction thus requires that the anti-creeper shall be expanded or sprung open when installed, and thereby utilize the resilient forces in the metal to maintain a friction grip on the rail. The clamping 10 on the rail may be accomplished in two ways. First, the anti-creeper may be placed on the rail by hand in approximately its correct position as shown in Fig. 3, except that the leg 1 of the V passed beneath the 15 rail will lie at such an angle that its hook will not clear the edge of the flange as shown at 6^a. A suitable wrench or tool may then be employed to spring the hook outward and upward into engagement as shown 20 in full lines. This method, however, is objectionable because of the extra tool and the skill required in the operation. To permit a second and more convenient method of installation, and to carry out one of the 25 primary objects of my invention, the configuration of the anti-creeper described is such that it can be sprung into its final seat by a blow from a hammer given with a normal downward stroke. In accordance 30 with the second method, the anti-creeper is applied by hand through the consecutive positions illustrated in Figs. 4 and 5, where the downwardly bent end 4 and the longitudinally disposed leg of the V are held 35 above the base flange in the fishing space of the rail, while the diagonal leg is passed beneath the rail. That the anti-creeper can be placed as in Fig. 5 in this manner will be apparent if note is taken of 40 the fact that because of its ultimate diagonal position the length of the leg 1 between the contact point 7 at the apex of the V and the contact point 9 of the hook at its end, is greater than the width of the rail 45 base. The anti-creeper is then rotated in a direction indicated by the arrow 11 in Fig. 5 about the diagonally disposed leg as an axis. This movement brings the 50 depending end 4 down over the edge of the base flange and simultaneously brings the upwardly bent hook to a slight incline over the edge of the opposite base flange. The rotative movement is made as far as possible by hand and then completed by a 55 downward hammer blow at the point and in the direction indicated by the arrow 12 in Figs. 1 and 2. To guard against the anti-creeper working off by a reversal of the rotative movement, the depending portion 60 4 is curved inwardly between the ends like the bill of a common gate hook, and to insure its always starting past the edge of the base when rotated from the position in Fig. 5, its lower end is curved outwardly 65 as shown. After the anti-creeper is sprung

onto the rail, the depending end may be brought into contact with the tie by one or two hammer blows applied at the apex of the V, as indicated by the arrow 13 in Fig. 3.

While it would be possible to remove the anti-creeper from the rail by a reversal of the installation movement just described, yet this would require a special tool, as in the ordinary conditions of track a hammer could not be applied to drive the depending end in an upward direction. I prefer, therefore, to remove the anti-creeper by a hammer blow on the end of the upturned hook 6 delivered in a downward and backward direction, as indicated by the arrow 14 in Figs. 2 and 3. This blow drives the hook down as shown in dotted outline in Fig. 2 until it clears the edge of the base, when the anti-creeper will come free. To this purpose the hook is made short and with only a slight amount of inclined overhang. It may be observed in this connection that the inclination or overhang of the hook 6 is utilized solely to hold the diagonal leg up to the rail base during installation and to keep it from working away in service. As illustrated in Figs. 3 and 6, the diagonal leg lies at an angle of about 60 degrees with the rail. This angle may be increased to a limit approximating 90 degrees, beyond which the distance between the apex of the V and the upturned hook will be so near the width of the rail base that it could not be readily applied thereto. It is evident, however, that within this limit an anti-creeper of the construction illustrated can be sprung on rails of different widths. The edge of a wider base is indicated by a dotted line at 16, Fig. 3, and the position of the upturned hook sprung outwardly for this width is shown in dotted outline at 6^b. If in this operation the V is opened up to or beyond the elastic limit of the metal, advantage is gained in the fact that the initial clamping grip of the anti-creeper on the rail is then equal to its full resilient contracting force. The anti-creeper is made, therefore, with the legs of the V at a smaller angle than required by the narrowest rail base in connection with which it is to be used, and within definite limits is adjustable for application to rails of greater width. Furthermore, an exact fit of the anti-creeper to the thickness and slope of the base flange is not essential to its functional operation, as is the case in many types where the initial grip depends upon the closeness of the fit of flange engaging jaws or the like. Consequently, the vertical space between the overhanging portion 3 of the longitudinal leg 2 and the diagonal leg 1 can be made large enough for the thickest flange of the different sized rails on which the anti-creeper is to be used.

The functional or operative action of my

anti-creeper is based on a lever-grip which in turn is dependent upon an initial friction grip at the points of fulcrum. The lever-grip is well known and in common use in the mechanic arts and need not be explained, but its peculiar double use in my invention is to be noted. Referring to Fig. 1, it will be observed that the reaction of the tie 18 in preventing movement of the rail toward the left will tend to rotate the pendant 4 in a vertical plane and in a direction counter-clockwise about its point of friction contact with the edge of the rail base at 8. With increased pressure, this movement brings the contacting portion or seat of the anti-creeper device at 8 into snug bearing with the corner between the upper surface and edge of the base flange of the rail and also brings the contacting portion or seat at 7 into snug engagement with the corner between the under surface and edge of the flange. In this way, a lever-grip of the anti-creeping device upon the rail that operates in a vertical plane, is established. Should the anti-creeper tend to yield to the reaction pressure of the tie by sliding along the flange, a second lever-grip comes into action in a horizontal plane with the contacting portions of the anti-creeper seats at 7 and 9 acting as fulcrums.

The novel feature of my invention involving the use of substantially only three seats or points of bearing, is fundamental to its construction.

Referring back to the method of installation where the anti-creeper is rotated into position, it will be apparent that during the process of rotation there can be only two points of simultaneously effective contact with the rail base on the center line of rotation, that is, a line through the points of contact 7 and 9, and that only one other part of the device, the depending end 4, is in effective contact, and that at the end of the movement this third contact is established at point 8. Now since the overhang of the longitudinal leg is made to clear the thickest flange, it also will be apparent that when brought into functional operation by the reaction of the tie, this leg will be out of effective contact with the flange except at a point closely adjacent the point 8 of the pendant 4, as indicated in Fig. 2. It is immaterial as to whether the diagonal leg 1 is in contact with the rail between the seats 7 and 9. Instead of allowing the round surface of the bent rod to find its own seats on the rail, I might in the manufacturing process form well defined seats at these three points holding the balance of the anti-creeper entirely free from the rail without in any way changing the novel features of my invention. It is further to be noted that no one of the seats however formed need be in itself a lever-grip on the rail.

It is possible to use my anti-creeper with auxiliary parts. For instance, I may introduce a separate intermediate clip with a broader tie bearing surface. Such a construction is illustrated in Figs. 6 and 7, in which a clip 19 having one bottom lip 20 and two top lips 21 and 22 engaging the base flange, is held on the rail by the depending end of the anti-creeper which is forced between the top lips. The clip has a tie abutting plate 23 stiffened by a bracket 24 rising into the bottom lip. The reaction thrust of the tie is transmitted through the clip to the anti-creeper proper, and the functional action of the latter is the same as without the clip.

It is obvious that changes may be made in the details set forth without departure from the essentials of the invention as defined in the claims.

What I claim as new and desire to secure by Letters Patent is—

1. An anti-creeping device for railway rails comprising a contracting clamp adapted to grip the flanges of the rail base when sprung into position thereon and having two seats for effective contact with one flange and a single seat for effective contact with the other flange, and having a resilient yielding connection between said single seat and one of the other seats, whereby the said clamp can be forced into position on the rail.

2. An anti-creeping device for railway rails comprising a contracting clamp adapted to grip the flanges of the rail base when sprung into place thereon and having three seats for effective contact with the base flanges, one of which is brought into effective contact, in the process of seating, by the rotation of the device about a line connecting the other two seats and while the latter engage opposite flanges.

3. An anti-creeping device for railway rails comprising a contracting clamp adapted to grip the flanges of the rail base when sprung into place thereon and having three seats for effective contact with the base flanges, one of which seats is brought into contact, in the process of seating, by rotating the device about a line connecting the other two seats, and while the latter engage opposite flanges, the connection between said first seat and that for engaging the opposite flange being elastic and resilient, whereby the said clamp may be seated on rails of variable widths of base.

4. An adjustable anti-creeping device for railway rails comprising a clamp adapted to hold the base of the rail with a lever-grip when placed in operative position thereon and having a tie abutting pendant, two seats for effective bearing on one base flange, a single seat for effective bearing on the opposite base flange, and a resilient elastic construction in the connections between the

seats, whereby the space to be occupied by the rail base may be expanded to suit the width of said rail base when seated therein.

5. An anti-creeping device for railway rails comprising a clamp adapted to be sprung into position on the rail and having a tie abutting portion and three seats of effective bearing on the rail base, whereby the reaction thrust of the tie acting through 10 the said abutting portion and the said three seats establishes a double lever-grip on the rail.

6. An anti-creeping device for railway rails comprising a spring clamp having two 15 effective seats on opposite rail base edges and a third seat adapted to be sprung into effective position on one of said rail base edges by a downward movement of rotation about a line through the other two 20 seats.

7. An adjustable anti-creeping device for railway rails comprising a contracting clamp adapted to grip the flanges of the rail base 25 when sprung into place thereon and having three seats for effective contact with the base flanges, the said three seats being applicable to flanges of any standard thickness, and a resilient elastic connection between at least two of said seats whereby 30 the said clamp may be sprung into place on rails having base flanges of varying widths.

8. An anti-creeping device for railway rails comprising a contracting clamp adapted 35 to grip the rail base when sprung into place thereon and having three seats for effective contact with the base flanges, one of said seats being arranged to engage one

flange and being connected with the two seats that engage the opposite flange in a resilient relation therewith, whereby when 40 the single seat is driven clear of the base flange by a downward blow of a hammer the said device will clear the rail and have a rail base seating space narrower than the rail base. 45

9. An anti-creeping device for railway rails comprising a contracting clamp adapted to grip the rail base when sprung into place thereon and having three seats for effective bearing on the base flanges, and an 50 elastic resilient construction in the connections between the seats, whereby the said device may be sprung into position on the rail by a downward blow applied adjacent one of said seats and sprung off of the rail by a downward blow applied adjacent the seat on the opposite base flange. 55

10. A resilient V-shaped rail anchor adapted to be sprung in place upon the rail base and comprising an inclined transverse member adapted to extend beneath the rail, and a longitudinal member arranged to overlap one of the base flanges thereof, and having rail engaging seats at its apex and 60 at the ends of said members, the seat at the apex and at the end of said longitudinal member being arranged to engage one base flange and the seat at the end of the transverse member being arranged to engage the 65 opposite base flange. 70
